CLAIM

We claim the ornamental design for a device mount, as shown and described.

DESCRIPTION

FIG. 1 is a top perspective view of a device mount.

FIG. 2 is a bottom perspective view thereof.

FIG. 3 is a front elevation view thereof, the rear, right-side,

and left-side views are identical to the front elevation view.

FIG. 4 is a top plan view thereof; and,

FIG. 5 is a bottom plan view thereof.

1 Claim, 5 Drawing Sheets
